ELECTRIC LAMP RECEPTACLE FASTENING MEANS

Frank E. Johnson, New Bedford, Mass., assignor to John I. Paulding, Inc., New Bedford, Mass., a corporation of Massachusetts

Application August 13, 1928. Serial No. 299,367

1 Claim. (Cl. 173—339)

This invention relates to electric lamp receptacles and more particularly to means for fastening receptacles of this character in illuminated signs.

5 Electric illuminated signs are generally made of thin sheet metal provided with circular holes for receiving and holding electric lamp receptacles, the holes being positioned and arranged to form letters or designs. In some cases, the 10 circular holes are provided with a pair of oppositely disposed open recesses or radial slots for receiving fastening means for holding the receptacles in position on the sign board. In such cases, the receptacle is mounted on the back side 15 of the sign board with a circular lip fitting within the hole and is held thereon by suitable screws or other devices threaded into the receptacle and having their heads overlapping the side edges of the radial slots. One disadvantage of this 20 method of fastening the receptacles onto the sign boards is that it requires the services of two men, one in back of the sign board to place the receptacle and the other in front to adjust the fastening means. Another disadvantage of this 25 method is due to the fact that such sign boards are generally placed in positions where they are caused to sway or move by wind pressure and breakages of the receptacles are frequent because of lack of resiliency in the fastening means. 30 One of the objects of the present invention is the provision of means for fastening electric lamp receptacles on a sign board which means is of such construction that the receptacles may be placed in position and fastened to the board by 35 one man operating in the back of the board.

Another object of the invention is the provision of fastening means which is resilient and will yield to compensate for any movement of the sheet metal sign thereby preventing breakage of 40 the receptacles.

A further object of the invention is to provide fastening means so designed that the receptacles may be mounted on the sign board rapidly and with a minimum of labor and effort and which 45 may be made at a very low cost and yet which is simple and efficient.

Other objects of the invention will be more specifically set forth and described hereinafter.

My invention contemplates a lamp receptacle 50 adapted for use on illuminated sign boards which is provided with a pair of oppositely disposed fastening members having portions on the front face of the receptacle adapted to overlap the edges of the radial slots in the sign board to hold 55 the receptacle thereon. The fastening members are resiliently mounted in the receptacle so that they will yield slightly in case there is any movement of its sign board in order to prevent breakages of the receptacles. The fastening means 60 are mounted in recesses opening from the back

of the receptacle and connected to the front face thereof by bores which permit the means to be manipulated from the back of the receptacle in the fastening operation. This feature of the invention makes it possible for one workman to 65 install the receptacles from the back of the board and to fasten them in position on the board with great rapidity and a minimum of effort thereby effecting economies of time and labor over the methods heretofore in use.

In the accompanying drawing illustrating one embodiment of the invention, Figure 1 is a front elevation of a portion of a sign board and a receptacle fastened thereto in accordance with my invention; Figure 2 is a plan view of the bottom 75 face of the receptacle; Figure 3 is a view on an enlarged scale partly in elevation and partly in section of the receptacle fastened to a sign board; Figure 4 is a sectional view of a portion only of the receptacle also on an enlarged scale, showing 80 one of the fastening members in unlocked position; and Figure 5 is a view in perspective of one form of fastening means comprising a plate having spring sides.

Referring to the drawing, 10 indicates a lamp 85 receptacle made from any suitable insulating material such as rubber composition, fibre or porcelain or other molded material having in its upper face a central socket recess 12 within which is fastened by two screws 14 a threaded metallic shell 16 for receiving the lamp. The closed end or portion of the shell is cut out to receive an elevated portion 18 formed on the bottom of the socket recess 12 which locks the shell against rotation and at the same time insulates 90 it from the central lamp terminal 20 mounted within a depression 22 in the portion 18.

The outer bottom face of the receptacle has two separate recesses 24 and 26 formed therein for receiving a straight wire terminal 28 and a 100 curved marginal wire terminal 30 respectively provided with binding screws 32 and 34 respectively. The wire terminal at 28 is connected by a screw 36 to the central lamp terminal 20 which screw serves to hold both members in place 105 and the curved wire terminal 30 is connected at its two ends to the shell by the two screws 14 and is further held to the receptacle by a screw 38. Both recesses open out on each side at 39 to permit the circuit wires to be connected to the 110 binding screws on the terminals from either side.

For fastening the receptacle to a sign board 40 the top or front face of the receptacle is provided with a circular lip 42 adapted to fit in a circular hole 44 in the sign board to prevent lateral movement of the receptacle thereon and mounted on the receptacle are fastening means 45 adapted to extend through two oppositely disposed slots or recesses 46 of identical form opening into the hole 44 and to overlap the edges of 120

said recesses on the front face of the sign board. The fastening means are preferably permanently mounted on the receptacle so that the two may be treated as a unitary structure.

5 The receptacle is preferably provided with two oppositely disposed lugs or ears 50 and 51 for carrying the fastening means, each ear having a bore 52 formed therein opening from the bottom face of the ear, which bore is connected by a bore 54 of smaller diameter to the top face of the ear thereby forming a square shoulder 56 at the top of the larger bore. To relieve the strain on the ears the bores 52 may be partially formed in the main body of the receptacle as shown in Figure 3 at 58.

10 In the preferred form of the invention two fastening members of different construction are provided for each receptacle, one of the members being so formed that one side of the receptacle may be slipped in place on the sign board without requiring manipulation of that member and the other side is then fastened to the sign board by merely turning the other fastening member through an arc of approximately ninety degrees.

15 The first member comprises a thin square plate 60 (Figure 5) centrally threaded on the end of a screw 62 mounted in the bore 54 of the ear 51 with its head in the bore 52 overlapping and in engagement with the shoulder 56. The two sides 20 64 adjacent the outer end of the plate 60 are depressed to form resilient spring members and the outer end 66 is flared upwardly. The top surface of the ear 51 may be provided with a raised or elevated portion 68 to fit into the plate between the depressed side portions thereof to prevent the plate turning on the screw 62 and the outer edge of the ear is bevelled at 70 to facilitate the slipping of that side of the receptacle in place on the sign board. The inner edge of 25 the plate 60 normally engages the lip 42 which also contributes to preventing the plate turning on the screw 62.

30 The second fastening means comprises a T-shaped member having a head 72 on the top face of the ear and a shank 74 mounted in the bore 54 and extending downwardly into the bore 52 and having its end split to form two prongs 76 turned outwardly to hold on said shank a washer 78 and a helical spring 80 abutting at 35 its lower end said washer and at its upper end the shoulder 56. The spring is normally under 40 compression to force the T-shaped member downwardly. In Figure 4 the T-shaped member is shown with one end of its head portion 72 locked in a depression 82 in the circular lip 42 so that the receptacle is prepared for presentation to the sign board.

45 In mounting the receptacle in the opening 44 of a sign board, the workman stands back of the board and presents the receptacle to the opening in position to receive the two edges of one slot opening 46 between the flared edge 66 of the plate 60 and the bevelled portion 70 of the ear 51. He then moves the receptacle radially of 50 the opening 44 and along the slot to force the edges thereof between the depressed sides 64 of the plate 60 and the top face of the ear 51 and continues this movement until the circular lip 42 slips into the opening 44 and the head 72 of the 55 T-shaped fastening member through the other slot 46. With an ordinary screw driver or similar tool inserted between the prongs 76, the workman then turns the said member approximately a quarter circle into the position shown in

60 Figure 1 and releases it. The spring then forces the fastening member downwardly with its head across the slot thereby completing the locking of the receptacle to the sign board. To remove the receptacle from the sign board, the fastening member is pressed outwardly by the use of a screw driver and turned until one end of the head slips into the depression or notch 82 when that side of the receptacle may be withdrawn from the opening 44 and the separation from the board then completed by a sidewise movement to withdraw the plate 60 from the other recess. The operations of fastening the receptacle in place on the board or removing it therefrom, are 65 extremely simple and may, with a little practice, be performed in a moment of time. After the receptacle has been fastened in place there is no danger of separation because of vibration of the board or other cause since the T-shaped fastening member is prevented by the lip 42 from turning to a position where its head can pass through the slot.

70 It will be observed that the receptacle is held locked on the sign board by means which are resilient and which will yield to compensate for vibrations of the sign board and thereby breakages of the receptacle are avoided. The T-shaped fastening member is held by the spring 80 which will yield, when there is movement of the sign board, sufficiently to relieve the receptacle from strain on that account and the same is true of the depressed sides of the plate member 60.

75 It is to be noted that in addition to the advantages of my invention already pointed out, the work of mounting receptacles on signs may be performed rapidly by one workman on the rear side of the board and thereby effects a material saving in the work of preparing an illuminated sign for the reception of the lamps.

80 My invention is capable of use with receptacles of various forms and the receptacle herein shown and described is illustrative only of such use.

85 It is to be understood that my invention is not to be limited to the exact forms herein shown and described since it may be embodied in other constructions all within the purview of the following claim.

90 What I claim is:

95 In an electric sign, the combination of a thin metal sign board having an opening and a pair of communicating slots therethrough, a lamp receptacle having a flange adapted to pass through said opening and a face adapted to abut the rear face of said board, said face having a projection adapted to fit one of said slots, a rectangular plate fixedly secured to said projection and having resilient depressed side portions, said plate being adapted to be passed through said opening from the rear side of said board and over one of said slots with its side portions overlapping the edges thereof to lock one side of said receptacle to said board, and a rotatable member resiliently mounted in said receptacle and having a T-shaped head projecting from said face and adapted to be passed through the other of said slots and to be turned cross-wise, said slot to lock the other side of said receptacle to said board, said member having its inner end formed for permitting it to be rotated from the rear side of said board.

100 FRANK E. JOHNSON.
